UNITED STATES PATENT OFFICE.

JULIUS H. SCHLAFLY, OF CANTON, OHIO, ASSIGNOR, BY MESNE ASSIGNMENTS, TO THE BERGER MANUFACTURING COMPANY, OF CANTON, OHIO, A CORPORATION OF OHIO.

TRUSSSED BEAM.

Application filed August 17, 1925. Serial No. 50,750.

The invention relates to the construction of beams which may be made of pressed steel chord members and an expanded metal web member secured together, and the object of 5 the improvement is to provide a beam structure in which there is a proper and the most efficient apportionment of the metal in the chord and web members.

The object of the improvement may be 10 attained by making the web member of a metal strip laterally slit and longitudinally expanded to form one or more rows of diamond mesh or the like, and making the chord members of a pair of pressed or rolled 15 angle strips, between which the edges of the expanded strip may be secured by welding, riveting or like means.

The invention is illustrated in the accompanying drawing forming part hereof, in 20 which—

Figure 1 is a side elevation of a short section of the improved beam, showing one form of the chord members, with parts broken away to illustrate the method of assembling the members;

Fig. 2, a cross section of the same on line 2—2, Fig. 1;

Fig. 3, a side elevation of a short section of the improved beam, showing another 30 form of the chord members, with parts broken away to illustrate the method of assembling the members;

Fig. 4, a cross section of the same on line 4—4, Fig. 3;

Fig. 5, a side elevation of a short section of the improved beam, showing a modified form of expanded web members, with parts broken away to illustrate the method of assembling the members; and

Fig. 6, a plan of a metal strip, laterally slit for longitudinal expansion, for making the modified form of web member.

Similar numerals of reference indicate corresponding parts throughout the drawing.

The web member, indicated generally by 7 or 7^a, may be made of a heavy gauge sheet metal blank 7^b, transversely cut to form staggered slits 8, and longitudinally expanded to form a series of bonds 9 and 9' and intervening strands 10, which may be in the form of well known diamond mesh.

The web strip is slit and expanded so as 55 to form a row of bonds 9 along each edge portion thereof, and these bonds may be

extended in length so as to substantially equal the width of the flanges of the chord members between which they are to be secured, and also be originally formed or subsequently pressed into the same common 60 plane.

The chord members may be made of two 65 separate angle strips 11, reversely positioned so that one flange 11' of each strip will abut the opposite sides of the edge bonds of the expanded strip web member, and the other flanges 11'' will extend therefrom in line with each other to form a bearing face for the beam of such width as may be desired. Upon the edge of each face flange may be 70 formed L-flanges 12 to give the combined chord members a channel strength.

The edge bonds 9 of the expanded strip web may be clamped and secured between 75 the abutting flanges 11 of the chord members, as by spot welding 13, as shown in Figs. 1 and 2; or in the modified form, shown in Figs. 3 and 4, each chord member may be made of a sheet metal strip folded 80 upon itself and bent from two reversely positioned angles between which the edge bonds of the web member are secured. In this form of construction, suitable apertures 12'', are provided in the folded edge, through which the edge bonds 6 of the web member may be passed for the purpose of 85 assembling the parts, after which the edge bonds are secured between the inturned flanges of the chord members as by spot welding.

By varying the particular dimensions and shape of the chord members, and the particular style and mesh of the web member, the amount of metal in the chord and web members, respectively, can be controlled so 95 as to conform exactly to the strength desired in each element or part of the trussed beam structure.

And by not slitting and expanding end portions 14, and intermediate portions 14' 100 of the sheet metal strip blank, these portions will form transverse spacing plates 14^a or spacing strips 14^{a'} in the web member, which will strengthen and stay the chord members at the ends and at intermediate points of the trussed beam; as shown 105 in Fig. 5.

I claim:

1. A trussed beam including a transverse- 110 ly slit longitudinally expanded web mem-

ber, and an angle strip chord member on the trussed beam, comprising a strip folded sides of the edges of the web member, there being unexpanded portions of the web member for spacing and staying the chord members, and means securing the web and chord members together.

2. A sheet metal chord member for a

trussed beam, comprising a strip folded upon itself and bent to form reversely positioned angles, with apertures in the folded edge for receiving portions of a web member. In testimony that I claim the above, I have hereunto subscribed my name.

JULIUS H. SCHLAFLY.
